UNITED STATES PATENT OFFICE.

ALEXANDER SZARKA, OF ROEBLING, NEW JERSEY, AND ALEXANDER PALFY, OF BUDAPEST, HUNGARY.

SAFETY ENVELOPE.

Application filed December 8, 1925. Serial No. 73,979.

This invention relates generally to envelopes and more particularly to means for securely sealing envelopes and to means for detecting tampering with sealed envelopes.

5 An object of the invention is to provide an envelope that may be readily sealed to safely hold the contents thereof.

Another object of the invention is to provide an envelope comprising means whereby any unauthorized tampering with the 10 same after the sealing thereof will be detected.

Other objects and advantages will be apparent from the description to follow taken 15 in conjunction with the accompanying drawing in which—

Figure 1 is a rear view of an envelope embodying the present invention, the top flap of the envelope being in open position.

20 Figure 2 is a view similar to Figure 1 but with the top flap in closed position.

Figure 3 is a rear view showing the improved sealing device about to be placed in effective position.

25 Figure 4 is a rear view of the improved envelope in sealed position with the improved detecting device applied thereto.

Figure 5 is a rear view of a modification of the improved envelope.

30 With particular reference to the drawing, the improved envelope consists of a rectangular front portion 10, top flap 11, side flaps 12, and bottom flap 13, said flaps 11, 12 and 13 comprising the rear portion of the envelope 35 when completed. Formed in the top flap 11 and disposed centrally thereof is a slot 14, and formed in the bottom flap 13 and disposed centrally thereof is a slot 15. Formed in the side flaps 12 and disposed substantially 40 centrally thereof are slots 16.

Arranged parallel with the top and bottom flaps 13 and 13, respectively, is a narrow split ring portion 17, preferably made of the same material as the envelope, said ring portion passing through the slots 16 to the interior of the envelope and having its edges 45 18 glued or otherwise secured to the inside surface of the side flaps 12. This ring portion 17 reinforces the envelope and conceals the points where the edges of the side and bottom flaps meet thereby adding to the attractiveness of the envelope.

Disposed at right angles to the ring portion 17 is a narrow elongated sealing strip 19, one terminal 20 thereof being glued or other-

wise secured to the inside surface of the side and bottom flaps, the strip 19 passing through the slot 15 to the exterior of the envelope. This strip 19 is creased at the points 21, 22 and 23 and may be pointed at its other terminal 24. The inside surface of the portion 25 of the strip 19 between the creases 21 and 22 and the inside surface of the portion 26 of the strip between the creases 22 and 23 are glued for a purpose which will be explained.

In order to seal the envelope, the top flap 11 is folded over the side flaps 12 and secured on them in the usual manner, its point being tucked underneath the ring 17. The terminal 24 is grasped and the portions 26 and 27 are folded over each other so that the terminal 24 is adjacent the crease 22. The crease 23 is then forced through the slot 14 as shown in Figure 3 carrying the portions 26 and 27 50 of the strip 19 with it to the interior of the envelope, the inward movement of said portions being stopped by the crease 22 engaging the slot 14. When in such effective position, the glued surface of the portion 26 will rest 55 against the interior surface of the top flap 11 and side flaps 12, and the glued surface of the portion 25 will rest against the exterior surface of the bottom flap 13, of the ring 17 where it crosses the same and the exterior surface of the top flap 11, and said glued surfaces being previously moistened, pressure exerted across the strip 19 will securely seal the parts of the envelope together thus holding 60 the contents safely therein. If a slight portion of the terminal 24 of the strip 19 protrudes after the envelope is sealed, such protruding portion may be cut off at the slot 14 so that no protruding edges remain.

In order to discover any tampering with 65 the envelope after it is sealed, any mark or indicia may be stamped over the strip 19, ring 17, top, bottom and side flaps, said stamp comprising lines crossing uniformly over the various parts. In Figure 4 is illustrated a 70 stamp in the form of a double circle 28, with its lines crossing all of the aforesaid parts of the envelope, and any tampering with the envelope would destroy the uniformity of 75 said lines.

In the modification illustrated in Figure 5, there is a slot 29 formed in the bottom flap 13 adjacent its upper edge, and another slot 30 formed in said bottom flap 13 adjacent its lower edge in alignment with the slot 29. An 80

elongated sealing strip 31 forms a continuation of the top flap 11, said strip 31 being creased at the point 32. The interior surface of the strip 31 as viewed in Figure 5 is glued. 5 To seal the envelope the terminal 31 of the strip is forced down through the slot 29 to the inside of the envelope and outwardly through slot 30 and the strip 31 is then creased at the point 32 and the exterior portion thereof glued to the rear of the envelope as will be understood.

The numeral 33 indicates the tip of sealing strip 31, which may be made rounded as shown in Fig. 5, for the sake of attractive 10 appearance.

We claim:

1. In an envelope having a back, side flaps and top and bottom flaps, a slot in each, a securing strip pasted to the inside of the bottom and side flaps at their meeting points in about the center of the formed envelope 20 and passing through the said slot in the bottom flap to the outside, said projecting free portion of said securing strip being creased to form a relatively stiff folded portion 25 adapted to be inserted into the envelope through the slot in the top flap with the bend

of said folded portion first, said folded portion being glued to be secured to the inside of said envelope, and a second securing strip 30 passing through the slots in the side flaps, its ends being pasted to the inside of the envelope.

2. In an envelope as set forth in claim 1, in which the free end of said folded portion is not glued and is adapted to manipulate said strip therewith when the end of the same is passed through the slot in the top flap. 35

3. In an envelope as set forth in claim 1, a base ring strip arranged in a transverse manner across the back of the envelope and across the ends of the sealed flaps, passing through two vertical slots in the side flaps to the inside of the envelope, the ends of the same being secured to the inside of said flaps, said securing strip crossing said base ring strip and being pasted thereon in the operation of sealing the envelope. 40

Signed at Roebling, in the county of Burlington and State of New Jersey, this 27th day of May, A. D. 1925, and at Budapest, Hungary, July 23rd, 1925, respectively. 45
